UNITED STATES PATENT OFFICE.

SIGVALD ALFRED CHRISTIAN KRISTENSEN, OF FREDERIKSBERG, NEAR COPENHAGEN,
DENMARK.

PROCESS FOR PRODUCING PRINTING-PLATES OF SLIGHT WEIGHT.

1,177,635.

Specification of Letters Patent.

Patented Apr. 4, 1916.

No Drawing.

Application filed July 14, 1914. Serial No. 850,983.

To all whom it may concern:

Be it known that I, SIGVALD ALFRED CHRISTIAN KRISTENSEN, stereotypist, subject of the King of Denmark, residing at 2 Neumannsvej, Frederiksberg, near Copenhagen, Denmark, have invented certain new and useful Improvements in Processes for Producing Printing-Plates of Slight Weight, of which the following is a specification.

10 The great demands made to the daily press and the illustrated press in respect to pictorial records of things and events, immediately after they have become interesting or have happened, have made it necessary for the printing establishments to acquire, very quickly, a printing block of the interesting object or event concerned. It has been attempted, heretofore, to satisfy this demand by producing, at a graphic establishment as near as possible to the locality where the object concerned is found or the event has happened, a number of prints, for instance photographic ones, from a photographic negative taken of the object or the 20 event and to send such photographs to the various printing houses or to other graphic establishments, and each of these would then, independently, produce from the print the blocks required—or paper flongs for 25 stereotyping have been sent, and the printing houses or other graphic establishments have then, by stereotyping, produced the requisite printing blocks from the flongs. An essentially more complete solution of the 30 problem it would be, however, if the graphic establishment producing the original record, for instance a photographic negative of the object or event concerned, were enabled to produce, quickly and with certainty, a number 35 of fully finished printing plates, adapted to be forwarded quickly by mail, *i. e.* by ordinary letter mail. Such plates are required, according to the nature of the matter, to be very light besides possessing the 40 properties desirable from a purely typographic point of view, for instance to be flexible, in order that they may be used in ordinary presses or in rotary presses, as the case may be. It has been proposed, as a 45 solution of this problem, to use a layer of unsized paper coated by a paste consisting of a metal powder stirred into a powerful adhesive, such paste possessing the property of becoming quite hard when drying. The 50 material thus prepared would be rapped

into a matrix by means of a brush, and it would then be coated, at the rear side, by some suitable substance.

The present invention, on the contrary, has for its object that the said unsized paper (tissue paper) or some other suitable fibrous substance is first placed on and caused to adhere to a thin sheet of some plastic substance, for instance celluloid, and then coated with a paste of the said kind whereafter the material thus produced is impressed into a matrix suitable for this purpose by using, if necessary, a slight heating in connection with the pressure. Hereby a possibility is opened for the production, in really great quantities, of printing plates of slight weight. When celluloid is used as a backing, it will be attained, by employing heating and pressure, that the coating of tissue paper will be able to adhere to the backing without adhesives having to be used and thus the smoothest possible surface will be attained. The layer of tissue paper is coated, preferably, by a paste consisting of aluminium powder stirred into water-glass. The sheet thus prepared is imprinted in a matrix of the requisite fineness and hardness and, after shipment, the plate thus finished may be placed in the plane or cylindrical form, it being simply pasted on the form, previously cast with blank depressed portions, corresponding to the thickness of the plate.

The material used for producing the plates may be manufactured and kept in stock so that it is only necessary to impress the material on the matrix, heating it slightly perhaps, in order to produce any number of plates, fully finished. Thus the production of the plates, as well of their fitting into position, requires but vary short time.

As a die for the plates there may be used a lead matrix stamped from a book-plate of the usual kind. Such a matrix, however, will hardly be sufficiently fine or hard enough to stand the stamping of the plates. The best result is attained, according to this invention, by a matrix being stamped in easily fusible metal from the original printing plate, preferably a metal melting at about 100° centigrade and, suitably, being placed as a coating on a lead plate. This matrix is now stereotyped, there being used, preferably, in producing the paper flong a suitable paste, for instance the same as

the one used for the plates. In the paper flong thus produced, a negative cast is now made, in known manner, of type-metal or a harder alloy, this cast forming an excellent 5 matrix for stamping the printing plates in the above described manner. The lead plates with covering of easily fusible metal used in the preparatory stamping may be manufactured in quantities for keeping in 10 stock.

The matrix for stamping the printing plates may be made plane or cylindrical as desired, and the latter shape has the advantage of making it easy to effect a perfectly 15 mechanical manifolding of the final printing plates on a band of the said material drawn past the cylindrical rotating matrix and pressed against it.

Having now particularly described and 20 ascertained the nature of my said invention

and in what manner the same is to be performed, I declare that what I claim is:—

The process for producing, in quantities, printing plates of slight weight, said process consisting in first causing, solely by heat 25 and pressure, a layer of tissue paper to adhere to a backing of celluloid, second coating the tissue paper by a paste consisting of aluminium powder stirred into water glass, third impressing the flong thus produced into a matrix, and fourth drying the flong while pressed against the matrix. 30

In testimony whereof the foregoing specification is signed in the presence of two witnesses.

SIGVALD ALFRED CHRISTIAN KRISTENSEN.
